US00D931268S

(12) **United States Design Patent** (10) Patent No.: **US D931,268 S**
Wright et al. (45) Date of Patent: ** Sep. 21, 2021

(54) **SLEEVE FOR ELECTRONIC DEVICE**(71) Applicant: **CATALYST LIFESTYLE LIMITED**,
North Point (HK)(72) Inventors: **Joshua Wright**, Hong Kong (CN);
June Lai, Hong Kong (CN)(73) Assignee: **Catalyst Lifestyle Limited**, Hong Kong
(CN)(***) Term: **15 Years**(21) Appl. No.: **29/677,855**(22) Filed: **Jan. 24, 2019**(30) **Foreign Application Priority Data**

Jul. 24, 2018 (CN) 201830401125.4

Primary Examiner — Lilyana Bekic*Assistant Examiner* — Mary Shannon Malley(74) *Attorney, Agent, or Firm* — Dinsmore & Shohl LLP(57) **CLAIM**

The ornamental design for a sleeve for electronic device, as shown and described.

DESCRIPTION

FIG. 1 is a front view of a sleeve for electronic device;
FIG. 2 is a back view thereof;
FIG. 3 is a left side view thereof;
FIG. 4 is a right side view thereof;
FIG. 5 is a top view thereof;
FIG. 6 is a bottom view thereof;
FIG. 7 is a front perspective view thereof; and,
FIG. 8 is an alternative perspective view thereof.
